UNITED STATES PATENT OFFICE.

ALEXANDER J. FEILD, OF RALEIGH, NORTH CAROLINA.

TOBACCO BOX OR CADDY.

SPECIFICATION forming part of Letters Patent No. 734,839, dated July 28, 1903.

Application filed June 10, 1902. Serial No. 111,045. (No model.)

To all whom it may concern:

Be it known that I, ALEXANDER J. FEILD, of Raleigh, in the county of Wake and State of North Carolina, have invented certain new and useful Improvements in Tobacco Boxes or Caddies; and I do hereby declare the following to be a full, clear, and exact description of the invention, such as will enable others skilled in the art to which it appertains to make and use the same.

This invention relates to that class of packing-boxes whose contents are of considerable weight or exert a considerable expansive force, being especially applicable to tobacco boxes or caddies, into which the contents are usually forced under pressure. Hitherto on account of the construction of such boxes it has been extremely difficult to open them and almost impossible to do so without destroying or more or less damaging one or more of the sides, resulting in removing or diminishing a needed protection to the contents while exposed for sale by retail.

The object of my invention is to provide a cheap box so constructed as to afford the desired strength and which at the same time may be easily opened without injury to those parts of the box which may serve as a cover or protection to the contents while being disposed of.

The invention will be hereinafter fully set forth, and particularly pointed out in the claims.

In the accompanying drawings, Figure 1 is a perspective view of a box or caddie equipped with my improvement. Fig. 2 is a vertical section on line $\alpha\alpha$, Fig. 1. Fig. 3 shows the securing means partly removed. Fig. 4 shows a slight modification.

Referring to the drawings, 1 designates a box designed to contain plug-tobacco or other articles which are packed under pressure or which are of considerable weight. The box may be of any desired shape, and on the inner faces of at least two of its opposite sides near one end are opposite grooves or recesses 2. These may be formed in all four sides of the box, if desired.

3 designates the main head or end cover, 50 designed to fit within the four sides of the

box, being in size equal to the internal diameter of the latter, so that while flush with the sides to prevent admission of air or moisture it is not tightly held as against withdrawal. 4 is a loop or tab which lies close to the main 55 head and by which the latter may be raised. At or near its center the head may, if desired, be provided with a slight cut-out or depression 5.

6 is the auxiliary head or end cover, designed 60 to serve as a stop or support for the main head 3. It consists of a thin panel made with and as a part of the box and held in place by being seated in the recesses 2. This auxiliary head if made in one piece may be provided 65 with a small slot or aperture 7 over and somewhat smaller in area than the depression 5. It may, however, be composed of several sections placed side by side, in which event some or all of the sections may have their edges 70 slightly cut away near their middle, as shown at 8 in Fig. 4.

The box thus constructed, with the main head 3 in place, is packed from the opposite end or head, which is left open for that purpose until the box is filled, when such end is closed and secured in any desired manner. When the box is being packed with tobacco and subjected to great pressure, it is proper to place it on the end or head equipped with 75 my improvement, having under it a block or board which will rest on the bed of the press and just fill the space between the press and the auxiliary head within the walls of the box, thus relieving such head from the usual 80 great strain thereon.

In order to open the box, the auxiliary head or end cover must be destroyed by being broken up and removed from the grooves. The panel or panels from which it is formed 90 being very thin, this is easily done with a pointed knife or chisel 9, inserted through slot 7, the depression 5 permitting it to reach the inner side of the panel. If several panels compose the head, the cut-aways 8 serve the 95 same purpose. The auxiliary head or cover being thus removed the main head or cover 3 may be easily removed by means of the tab or loop 4.

It will be observed that a packing-box em- 100

bodying my invention is cheap and substantial and may be easily opened without injury to the box proper.

I claim as my invention—

- 5 1. The combination with a packing-box designed to accommodate materials under pressure filling the space between its walls and ends, of a removable head of size equal to the internal diameter of the box, so that its edges are in the planes of the inner surfaces of the walls thereof, and a holder contacting with a face of such head for retaining the latter in place during shipment and until access is desired to the interior of the box, and entirely 10 covering one face of such head such holder being designed to be removed so that the head may be withdrawn and replaced, as set forth.
- 15 2. The combination with a packing-box designed to accommodate materials under pressure filling the space between its walls and ends, of a removable head of size equal to the internal diameter of the box, so that its edges are in the planes of the inner surfaces of the walls thereof, such box having inner grooves 20 near one end at a point just outside of the head, and a board of thin material fitted in said grooves and entirely covering one face of such head, such board being designed to

be removed to permit of the withdrawal and replacing of the head when access to the interior of the box is desired, as set forth. 30

3. The combination with a packing-box designed to accommodate materials under pressure filling the space between its walls and ends, of a removable head of size equal to the internal diameter of the box, such box having inner grooves near one end at a point just outside of the head, and a board of thin material fitted in said grooves, such board having an opening or openings therein, as and 35 40 for the purpose stated.

4. The combination with the box having opposite grooves on the inner faces of two or more of its sides, of a main head located within the box adjacent to such grooves and having a central depression, and an auxiliary head designed to be seated in said grooves and having a central slot or aperture, substantially as and for the purpose stated. 45

In testimony whereof I have signed this 50 specification in the presence of two subscribing witnesses.

ALEXANDER J. FEILD.
